UNITED STATES PATENT OFFICE.

FRED MAYER, OF PHILADELPHIA, PENNSYLVANIA.

POCKET CONSTRUCTION.

Application filed August 8, 1924. Serial No. 730,878.

My present invention relates to pocket constructions for outer garments and other articles of wearing apparel, such as sweaters, vests, jackets, sport-coats, and the like, for 5 men, women and children, and aims to devise articles of the general character specified above which will be simple in construction, easy and convenient to fabricate and to apply, which will be economical in the 10 amount of material required and in the labor and equipment needed for their fabrication, and which will be adapted in a simple and ingenious manner to provide means whereby, without necessitating the use of a flap, button or other fastening or protective means, the pockets of the garments of the present invention will be adapted to securely retain articles therein while permitting the ready 15 removal of such articles therefrom as and when desired.

In the accompanying specification I shall describe, and in the annexed drawing show, several illustrative embodiments of the articles of the present invention. It is, however, to be clearly understood that my invention is not limited to the specific embodiments thereof herein shown and described for the purposes of illustration only.

Referring to the drawing, wherein I have 20 illustrated the aforesaid illustrative embodiments of the present invention:

Fig. 1 is a plan view of one form of garment pocket made in accordance with the principles of the present invention;

Fig. 2 is a view similar to Fig. 1 of still another form of garment pocket made in accordance with the principles of the present invention; and

Fig. 3 is a view similar to Fig. 1 of still another form of garment pocket made in accordance with the principles of the present invention.

Referring now to the aforesaid illustrative embodiments of the articles of the present invention, and particularly to the drawing illustrating the same, these embodiments comprise a garment pocket, such as a pocket for outer garments and other articles of wearing apparel, such as sweaters, vests, jackets, sport-coats, and the like, characterized by having a restricted opening, such opening being preferably expansible, as by having the edge portion of the same made of an elastic or other readily expansible material. In certain of its forms the garment pocket of the present invention is of com-

paratively great extensibility at its opening or has an opening of reduced size but of comparatively great extensibility. For this purpose, the edge portion, at the restricted 60 opening of the pocket, may be made of elastic or other readily expansible material, such as knit fabric having vertically disposed wales, while the rest of the pocket is preferably made of material having comparatively slight expansibility in a direction transverse to the line of opening of the pocket, as by being made of knit fabric having 65 horizontally disposed wales.

For example, and referring now more particularly to the embodiment shown in Fig. 1 of the drawing, 10^a designates the main body portion of the garment to which the pocket, generally designated by reference character 11^a, is applied. The pocket 11^a has the opening 12^a defined by the facing portion 13^a, which is of a substantially inverted T-shaped form, the rest of the pocket being defined by the facing portion 14^a which is of substantially square or rectangular form. The facing portions 13^a and 14^a 70 may be joined to each other by the seam or other suitable securing means 15^a, while the pocket-defining portions 13^a and 14^a may be attached to the body portion of the garment 80 10^a by an edge seam, here indicated by reference character 16^a.

In the embodiment here illustrated, the portion 13^a, defining the pocket opening 12^a, is preferably made of knitted fabric having 90 its wales vertically disposed, so that the opening is expansible, the fabric of the portion 13^a being expansible in a direction transverse to the line of the pocket opening 12^a. The portion 14^a, in the example here given, 95 is likewise made of knitted fabric, but in this case the wales of the knitted fabric are horizontally disposed, whereby the fabric has comparatively little expansibility transverse to the line of the opening 11^a of the pocket. It will thus be apparent that this type of 100 construction satisfies the chief aims of a practical pocket construction of the type defined above.

Referring now to the form of the invention shown in Fig. 2 of the drawing, the garment portion 10^c has applied thereto a pocket 11^c having the restricted opening 12^c defined by the facing portion 13^c and the lower portion 14^c. The facing portion 13^c 105 is of a substantially trapezoidal form and is joined to the lower portion 14^c, which is of

a substantially square or rectangular form, by means of a line of stitching 15^c. The pocket portions 13^c and 14^c may be attached to the garment portion 10^c by means of the line of stitching 16^c.

As here illustrated the facing portion 13^c defining the restricted opening 12^c of the pocket 11^c is preferably made of knit fabric, the wales of which are vertically disposed, 10 thus permitting the restricted opening 12^c to be expanded or stretched in a direction transverse to the line of the opening 12^c, while the facing portion 14^c of the pocket 11^c, although made of knitted fabric, has 15 the wales of the same horizontally disposed so as to have comparatively little expansibility transversely to the line of the pocket opening 12^c. In this way the pocket will have the desired great degree of expansibility 20 adjacent the pocket opening, in the construction desired, while the main body portion of the pocket is without such extensibility, since the same is not desirable in the latter case.

25 In the form shown in Fig. 3 of the drawing the resulting pocket construction is quite similar to the form shown in Fig. 2 of the drawing except that the upper portion 13^d of the pocket 11^d, defining the restricted opening 12^d, is of a substantially square or rectangular form, as is also the case with the lower portion 14^d of the material defining the pocket 11^d, which latter is attached, as by the line of stitching 16^d, to the garment portion 10^d. A seam 15^d may be used to attach the upper portion 13^d of the pocket to the lower portion 14^d of the same. In this case, as in the case of the pocket shown in Fig. 2 of the drawing, the upper portion 13^d is made of knit fabric having vertically disposed wales, while the lower portion 14^d of the pocket has horizontally disposed wales, for reasons already set forth in detail above. The desired restricted form of the opening 12^d of the pocket 11^d is in this case obtained by two auxiliary lines of stitching 17^d and 18^d across the corners of the upper portion 13^d defining the pocket opening 12^d, thus providing a central portion 19^d of substantially trapezoidal form as in the case of the upper portion 13^c of the form of pocket illustrated in Fig. 2 of the drawing.

55 The manner of constructing the garment pocket of the present invention has been set forth in sufficient detail above. It will be noted that the construction is very simple and the garment pocket very easy to cut, shape and apply. The pocket constructions of the present invention, as illustrated 60 above, possess the great advantage that while being simple in construction, and easy and economical to fabricate, they permit the ready expansion of the restricted opening of the pocket to the desired size to admit articles to be deposited in such pockets, where-

upon the pocket contracts to its original size, due to the elasticity of the fabric or like portion defining the restricted pocket opening, whereby such articles are securely retained in the pockets until desired to be 70 removed therefrom, which operation may be readily effected by reason of the ready expansibility of the pocket opening. This type of pocket construction may be applied with great success to the various types of 75 garments enumerated above.

It may here be stated that the same desirable results may be obtained by properly stitching the top of the pocket, which may be of the usual rectangular or other regular 80 shape, so as to provide the necessary restricted or narrow opening at the top. In such a case, the material of which the pocket or pocket facing is made may consist of a single piece of fabric having a single degree of 85 elasticity, that is, for example, with the wales in longitudinal position so that the opening of the pocket has elasticity in a direction transverse to the pocket opening.

90 The purpose of having the different portions of the pocket or pocket facing so constructed and arranged as to have different degrees of expansibility in different directions is that, by having the pocket at its mouth or open portion of relatively great 95 transverse expansibility while the remaining portion of the pocket is of relatively slight transverse expansibility (the mouth or open portion being of relatively slight longitudinal expansibility while the remaining portion of the pocket is of relatively great longitudinal expansibility), the mouth of the pocket may be manipulated freely to admit the objects which are desired to be inserted 100 into the pocket without too readily distorting the mouth of the pocket, while still preventing the articles within the pocket from becoming too readily dislodged therefrom, the relatively slight transverse expansibility 105 of the remaining pocket portion permitting the same to maintain its shape even when the pocket is quite full.

110 What I claim as my invention is:

1. An article of wearing apparel comprising a main body portion, and a pocket-defining facing portion attached to said body portion, said pocket-defining facing portion having its open end of reduced size but of relatively great expansibility transversely as compared to the longitudinal expansibility 115 of said open end, the remaining portion of said pocket-defining facing portion being of relatively slight expansibility transversely as compared to the longitudinal expansibility of said remaining portion.

120 2. An article of wearing apparel comprising a main body portion, and a pocket-defining facing portion attached to said body portion, said pocket-defining facing portion having its open end of reduced size, the re- 125

maining portion of said pocket-defining facing portion being of relatively slight expansibility transversely as compared to the longitudinal expansibility of said remaining portion.

3. An article of wearing apparel comprising a main body portion, and a pocket-defining facing portion attached to said body portion, said pocket-defining facing portion having an open end portion of relatively great expansibility transversely as compared

to the longitudinal expansibility of said open end portion, the remaining portion of said pocket-defining facing portion being of relatively slight expansibility transversely ¹⁵ as compared to the longitudinal expansibility of said remaining portion.

In testimony whereof, I have signed my name to this specification this 29th day of July, 1924.

FRED MAYER.
